HOUSING SUPPORT

Filed May 1, 1933

A technical diagram of a book's fore-edge, showing the binding and the edges of the pages. The diagram is annotated with numbers 10, 11, 12, 13, 14, 15, 16, 17, 18, 19, 20, 21, 22, 23, 24, 25, 26, 27, 28, 29, 30, and 31. Callout 10 points to the top edge of the left page block. Callout 11 points to the top edge of the right page block. Callout 12 points to the top edge of the central page block. Callout 13 points to the top edge of the rightmost page block. Callout 14 points to the gutter area. Callout 15 points to the bottom edge of the central page block. Callout 16 points to the bottom edge of the rightmost page block. Callout 17 points to the bottom edge of the left page block. Callout 18 points to the bottom edge of the right page block. Callout 19 points to the top edge of the rightmost page block. Callout 20 points to the bottom edge of the rightmost page block. Callout 21 points to the top edge of the leftmost page block. Callout 22 points to the top edge of the rightmost page block. Callout 23 points to the top edge of the central page block. Callout 24 points to the bottom edge of the central page block. Callout 25 points to the bottom edge of the rightmost page block. Callout 26 points to the bottom edge of the rightmost page block. Callout 27 points to the bottom edge of the rightmost page block. Callout 28 points to the bottom edge of the rightmost page block. Callout 29 points to the bottom edge of the rightmost page block. Callout 30 points to the bottom edge of the rightmost page block. Callout 31 points to the bottom edge of the rightmost page block.

This technical drawing illustrates a car dashboard assembly, specifically the instrument panel area. The drawing is labeled with various numbers, likely referring to different parts or assembly steps. Key components labeled include:

- 13: Top left corner of the main panel.
- 10: Numbered on the left side of the main panel.
- 14: Numbered at the top center of the main panel.
- 38: Numbered at the top center of the main panel.
- 15: Numbered near the top right of the main panel.
- 34: Numbered near the top right of the main panel.
- 12: Numbered near the bottom center of the main panel.
- 24: Numbered near the top left of the main panel.
- 21: Numbered near the top left of the main panel.
- 27: Numbered near the center of the main panel.
- 33: Numbered near the top right of the main panel.
- 30: Numbered near the bottom left of the main panel.
- 16: Numbered near the bottom center of the main panel.
- 31: Numbered near the bottom right of the main panel.
- 25: Numbered near the top center of the right side panel.
- 18: Numbered near the top left of the right side panel.
- 26: Numbered near the top right of the right side panel.
- 22: Numbered near the bottom right of the right side panel.
- 33: Numbered near the bottom left of the right side panel.
- 17: Numbered near the bottom center of the right side panel.
- 15: Numbered near the bottom left of the right side panel.
- 23: Numbered near the bottom right of the right side panel.
- 30: Numbered near the bottom center of the right side panel.
- 31: Numbered near the bottom right of the right side panel.
- 19: Numbered at the top right of the right side panel.
- 11: Numbered near the bottom center of the right side panel.
- 10: Numbered at the bottom left of the right side panel.
- 5: Numbered near the top left of the right side panel.
- 1: Numbered at the bottom center of the right side panel.

The drawing also shows various internal components like gauges and mounting hardware. A handwritten label "Fig. 3." is present in the upper right corner of the drawing area.

HOUSING SUPPORT

Julius Ritter, Jr., Racine, Wis., assignor to Hartmann Trunk Company, Racine, Wis., a corporation of Wisconsin

Application May 1, 1933, Serial No. 668,690

8 Claims. (Cl. 190—38)

The present invention relates in general to improvements in housing supports, and relates more specifically to improvements in the construction and operation of mechanism for mounting containers such as trunks or chests having relatively movable closure sections.

An object of the invention is to provide an improved support for a housing having relatively movable closure sections, which will facilitate opening and closing of the housing while at the same time providing a suitable mounting for the closure sections.

Some of the more specific objects of the intervention are as follows:—

15. To provide a new and useful mounting for portable containers such as wardrobe trunks or chests having hingedly connected closure sections, which will permit convenient opening and closing of the container.

20. To provide an improved base for a wardrobe type of luggage carrier, which will enable easy loading and unloading of the carrier, and which will also facilitate movement of the container over the floor.

25. To provide an improved support for trunks or the like, which may be readily manufactured and applied to standard trunks as an accessory, without interfering with the storage space.

30. To provide an improved cabinet base which is simple, compact and durable in construction, and which is highly effective both as a support for the cabinet and as a means for facilitating opening and closing thereof.

35. These and other objects and advantages will be apparent from the following detailed description.

40. A clear conception of an embodiment of the invention and of the mode of constructing and of manipulating housing supports built in accordance therewith, may be had by referring to the drawing accompanying and forming a part of this specification in which like reference characters designate the same or similar parts in the various views:

45. Fig. 1 is a top view of the lower portion of a two section wardrobe trunk, showing the sections open in full lines, and closed in dot and dash lines;

Fig. 2 is a front elevation of the lower trunk portion showing the sections swung into open position and looking into the interiors thereof;

position and locking into the interiors thereof, Fig. 3 is a bottom view of the trunk showing the closure sections swung into open position, and also showing the supporting base in dot-and-dash lines;

Fig. 4 is a full bottom view of the trunk and base with the closure sections swung into closed position, the bottom plate of the base having been partly removed:

Fig. 5 is a radial section through the forward portion of the base and trunk, taken along the line 5-5 of Fig. 4; and

Fig. 6 is another radial section through the rear portion of the base and trunk, taken along the line 6-6 of Fig. 4.

While the invention has been illustrated and described herein as being specifically applied to a two-section wardrobe trunk wherein garments are capable of being hung vertically, it is not intended to limit the scope by such specific disclosure, and some of the novel features are obviously more generally applicable to housings of various types and to supports therefor.

Referring to the drawing, the trunk may be of the standard or conventional two section type having garment hanging space in one portion thereof and having drawers or the like in another portion thereof, and comprises a section 10 pivotally attached to a section 11 by means of

hinges 12, and latches 13 for locking the sections 10, 11 in closed position. The improved support or base structure which is common to both sections 10, 11 of the housing, may be attached as an accessory to any such conventional two section wardrobe trunk, and comprises a circular top base plate 14 having six anti-friction or ball bearings 15 mounted thereon and also having three rectilineal slots 16, 17, 18 therein, and a composite bottom ring or plate 19 detachably attached to the lower part of the plate 14 by means

of screws 20 or the like. The base and bottom plates 14, 19 may be formed of sheet metal, and the ball bearings 15 may be of standard caster construction comprising a ball rotatably confined within a sheet metal socket. The trunk sections 10, 11 are provided with rigidly attached lower bearing plates 21, 22 respectively, which rest directly upon the ball bearings 15 and along which the respective bearing balls travel during swinging.

the respective bearing balls travel during swinging of the sections 10, 11 as indicated by the path lines 23 in Fig. 3. Depending from the bearing plates 21, 22, are three guide elements or pins 24, 25, 26 which extend into and are movable

along the slots 16, 17, 18 respectively, and each of these pins has an enlarged lower head 27 for preventing the same from being withdrawn from the adjacent slot. Each of the pins 24, 25, 26, is moreover embraced by a set of roller bearings 28 which coact with the upper and lower surfaces of the base plate 14 adjacent to the slots

16, 17, 18 in order to insure free travel of the pins along the slots when the sections 10, 11 are opened and closed.

As shown in detail in Figs. 5 and 6, the lower forward portions of the closure sections 10, 11 are provided with arcuate locking strips 30 having inwardly extending flanges 31 adapted to enter peripheral outwardly open recesses 32 in the base plate 14; and the lower rear portions of the sections 10, 11 are provided with shorter arcuate locking strips 33 having outwardly extending flanges 34 adapted to enter peripheral inwardly open recesses 35 formed in an elevated portion 36 at the rear of the base plate. This construction is such that when the sections 10, 11 are in closed coaction, the flanges 31, 34 interlock with the recesses 32, 35 respectively to rigidly attach the base to the trunk, while at the same time presenting a peripherally smooth and finished appearance for the base structure. The lower ring plate 19 of the base may also coact with a protective filler plate 37 as shown in Figs. 5 and 6 in order to thoroughly conceal and protect the motion transmitting mechanism, and the bottom ring plate 19 may also be provided with button supports 38 as indicated in the drawing.

The improved base structure and motion transmitting mechanism, may be readily applied to the corresponding ends of the sections 10, 11 of a standard wardrobe trunk, by merely attaching the bearing plates 21, 22 to the sections 10, 11 with the aid of screws, bolts or rivets, and the locking strips 30, 33 and pins 24, 25, 26 may be rigidly attached to the plates 21, 22 while the pins 24, 25, 26 are retained within the slots 16, 17, 18 by the heads 27. After the base structure has been thus applied to the trunk, the sections 10, 11 are freely relatively swingable about the hinges 12, and the motion of one closure section is always transmitted to the other through the motion transmitting mechanism comprising the pins 24, 25, 26 coacting with the slots 16, 17, 18 respectively in the base plate 14. The weight of the trunk and its load, is carried by the ball bearings 15 coacting with the bearing plates 21, 22, and the ball bearings 28 eliminate excessive frictional resistance to movement of the pins 24, 25, 26 along the slots 16, 17, 18.

When the sections 10, 11 are swung from closed position as shown in dot-and-dash lines in Fig. 1, to open position as shown in full lines, the pins 24, 26 move from the inner extremities of the slots 16, 18 respectively toward the outer extremities thereof, and the pin 25 simultaneously moves outwardly toward the outer extremity of the central slot 17. Pressure applied to either closure section 10, 11 to produce swinging movement thereof, will obviously result in similar but opposite motion of the other section, and when the trunk has been fully opened, the pins 24, 26 will be in the extreme outer ends of the slots 16, 18 respectively, while the pin 25 will be at the extreme inner or forward end of the remaining slot 17 as illustrated in Fig. 1. Upon closing of the container, the pins 24, 25, 26 will obviously travel in reverse directions within their respective slots 16, 17, 18 and when the sections 10, 11 have been completely closed, the pins 24, 26 will be positioned at the extreme inner ends of the slots 16, 18 respectively whereas the pin 25 will repose at the extreme rear or outer end of the central slot 17. During such opening and closing movement of the closure sections 10, 11, the hinges 12 will travel forwardly and rearwardly in paths substantially parallel to the central slot

17, and the base will always provide a stable support for the sections 10, 11 whether open or closed. The ball bearings 15 coacting with the bearing plates 21, 22 will define paths substantially as indicated by the lines 23 in Fig. 3, and when the trunk is closed, the flanges 31, 34 of the strips 30, 33 respectively, will interlock with the recesses 32, 35 of the base to eliminate all looseness of parts and to present a neat appearance.

From the foregoing description it will be apparent that the invention provides an extremely compact and durable base structure for facilitating opening and closing of a trunk or the like, and for permitting movement of the container over a floor. The various parts of the base or support may be formed of sheet metal with the aid of punches and dies, in order to provide a rigid but light structure which may be produced at minimum cost. The cost of construction can also be reduced by utilizing standard ball bearings 15, 28, and these bearings permit convenient manipulation of the sections 10, 11. The floor space occupied by the base structure is obviously no greater than that occupied by the trunk when closed, and this base obviously prevents possible tipping of the sections 10, 11 when open and permits most convenient access to the interiors of these sections. The improvement has proven highly successful as applied to wardrobe trunk structures, but is obviously more generally applicable to other types of containers having hingedly connected closure sections.

It should be understood that it is not desired to limit the invention to the exact details of construction and operation herein shown and described, for various modifications within the scope of the claims may occur to persons skilled in the art.

It is claimed and desired to secure by Letters Patent:

1. A housing support comprising, a base formed symmetrical about a central vertical axis disposed substantially at the center of gravity of the base, a housing comprising relatively movable sections secured to said base, said housing when closed being disposed concentric with said axis and completely covering and interlocking with said base and when open having the interlock released and the center of gravity of the housing disposed rearwardly of the base axis and within said base, and mechanism interposed between said base and said sections and constantly located within the confines of said base for causing said sections to partake a definite path during opening and closing of said housing.

2. A housing support comprising, a circular base having a central vertical axis disposed substantially at the center of gravity thereof, a substantially square housing comprising relatively articulable half sections movably attached to said base, said housing when closed being disposed concentric with said axis and completely covering and interlocking peripherally with said base and when open having the interlock released and the rear wall of one section disposed substantially tangent with the rear peripheral portion of the base, and mechanism interposed between said base and said sections for causing the latter to partake a definite path during opening and closing of the housing.

3. A housing support comprising, a circular base having a central vertical axis, a substantially square housing comprising articulable rectangular sections each swingable through a quadrant arc and secured to said base, said housing

when closed completely covering and interlocking peripherally with said base and when open having the interlock released and the housing sections substantially alined and disposed across said base rearwardly of said axis, and mechanism interposed between said base and said housing for causing the swinging motion of one section to be imparted to the other.

4. A housing support comprising, a substantially circular base having three slots therein disposed at oblique angles to each other, a housing comprising hingedly connected sections swingable through substantially quadrant arcs during opening and closing of the housing, and three pins carried by said sections and coacting with said slots to cause the motion of one section to be imparted to the other, two of said pins being supported by one of said sections.

5. A housing support comprising, a substantially circular base, a housing comprising hingedly connected sections secured to said base and movable through substantially quadrant arcs to open and close said housing, and means for causing the ends of said sections to interlock with the periphery of said base when said housing is closed.

6. A housing support comprising, a base having

three slots therein disposed at oblique angles to each other, a housing comprising hingedly connected sections swingable through arcs during opening and closing of the housing, and three pins carried by said sections and coacting with said slots to cause the motion of one section to be imparted to the other, at least two of said pins being supported by one of said sections.

5

7. A housing support comprising, a base, a housing comprising hingedly connected sections secured to said base and movable through an arc to open and close said housing, and means for causing the ends of said sections to interlock with said base when said housing is closed.

10

8. A housing support comprising, a base having three slots therein disposed at oblique angles to each other, a housing comprising hingedly connected sections swingable through arcs during opening and closing of the housing, three pins carried by said sections and coacting with said slots to cause the motion of one section to be imparted to the other, two of said pins being supported by one of said sections, and means for causing the ends of said sections to interlock with said base when said housing is closed.
